UNITED STATES PATENT OFFICE.

HARRY E. BILGER, OF MONMOUTH, ILLINOIS.

COLLAPSIBLE FORM FOR CONCRETE CONSTRUCTIONS.

1,373,548.

Specification of Letters Patent.

Patented Apr. 5, 1921.

Application filed April 12, 1920. Serial No. 373,144.

To all whom it may concern:

Be it known that I, HARRY E. BILGER, a citizen of the United States, residing at Monmouth, in the county of Warren and State of Illinois, have invented a certain new and useful Improvement in Collapsible Forms for Concrete Constructions (Case 1), of which the following is a full, clear, concise, and exact description, reference being had to the accompanying drawings, forming a part of this specification.

My invention relates to a collapsible form adapted for use in constructing concrete culverts, bridges, sewers, aqueducts, etc. Among its salient objects, my said invention contemplates:

1st. The provision of an apparatus of this class that is of steel throughout, and which comprises a comparatively few large parts and no small parts that are apt to become lost or mislaid.

2nd. The provision of a form of this class which, when assembled, presents a flat top and straight vertical sides to the concrete which is poured around and over the form when the latter is used.

3rd. The provision of a form of this class that readily may be assembled, collapsed and disassembled by a single workman.

30 4th. The provision of a form of this class wherein all similar parts of the apparatus used in constructing a culvert, bridge or the like of any given size, are symmetrical and interchangeable to the end that the workman assembling the form is not required to distinguish between rights and lefts.

5th. The provision of an equipment comprising base members and cover plates capable of use in building up a form of any one 40 of a plurality of sizes, together with a plurality of sets of "form centers", each set of form centers to be used in erecting a form of a certain size.

6th. An equipment of the class mentioned, 45 all of the several parts of which are of metal and so constructed that if broken, they can be easily and quickly repaired by any blacksmith.

These and other advantages of the apparatus of my invention will more fully appear 50 as the following detailed description progresses. In the accompanying drawings illustrating my invention,

Figure 1 is a transverse, vertical, sectional view of a small sized form embodying my present invention, this view illustrating the

several parts of the form assembled and ready to have the concrete, which is to form the finished culvert, bridge or the like, placed over and around the same. 60

Fig. 2 is a longitudinal, vertical, sectional view taken on the line 2—2 of Fig. 1, certain parts of the apparatus being broken away because of lack of space on the drawing in which to illustrate the form without broken 65 parts on a sufficiently large scale.

Fig. 3 is a view in perspective of one of the two similar and interchangeable base members of the form of my invention.

Fig. 4 is a view in perspective, with certain parts broken away, illustrating the form 70 of the present invention in the course of assembly.

Fig. 5 is a detailed, sectional view taken on line 5—5 of Fig. 2, this view illustrating 75 the means carried by the form centers for spacing the base members.

Fig. 6 is a view similar to Fig. 5, illustrating a modified and perhaps preferred means carried by the form centers for the 80 purpose of spacing the base members.

Fig. 7 is a fragmentary side elevation of the form center parts shown in Fig. 6.

Fig. 8 is a view similar to Fig. 2, illustrating a form of greater height and width than 85 the form of Fig. 2, the scale to which Fig. 8 is drawn being such as to permit two of the form centers to be shown, whereas in Fig. 2 it has been possible to illustrate but one of the form centers. 90

Fig. 9 is a vertical, sectional view taken on the line 9—9 of Fig. 8.

Fig. 10 is a view in perspective of one of the cover plates forming part of the apparatus of my invention; and 95

Fig. 11 is a fragmentary, elevational view illustrating a modified form center construction.

Similar characters of reference refer to similar parts throughout the several views. 100

The apparatus shown in Figs. 1 to 5, inclusive, consists of base members 12—12, a plurality of form centers, one of which is illustrated at 13, a pair of corner cover plates 14—14, and a plurality of channel shaped 105 cover plates 15—15. In the description of the larger type of form shown in Figs. 8 and 9, I shall explain how these plates 15 may supplement the corner plates 14 in providing a flat top for the form. In the smaller form 110 of Figs. 1 to 5, inclusive, the plates 15 are employed merely at the sides of the form.

The details of one of the base members 12 are illustrated in perspective in Fig. 3. The base member 12 is substantially L-shaped in cross section. Welded, riveted or otherwise secured to each end of the base member 12 are short angle bars 16-16, the vertical legs of which abut against the vertical sides of the base member, the purpose of the angle bars 16 being to widen the bottom of the base member at its ends and thus prevent the base member from tilting over when in use. Also secured to the ends of the base member are the short angle bars 17-17, the horizontal sides of which project beyond the horizontal side of the base member and are disposed somewhat above the horizontal side of the base member. As will presently appear, the purpose of the angle bars 17 is to prevent the lateral pressure of the concrete 10 from forcing the lowermost side cover plates under the base members.

The vertical side of each base member is provided with a plurality of notches 18, there being one of these notches provided 15 for every form center employed. The top edge of the base member is inclined adjacent the notches 18, as is indicated at 19-19. If it were not for the fact that I contemplate using either base member on either side of 20 the form, it would suffice to incline the top edge of the base member only at one side of each of the notches 18. I prefer, however, to incline the top edge at both sides of each notch in order that each base member may 25 be used on either side of the form.

Each of the form centers of the apparatus shown in Figs. 1 to 5 comprises a steel plate 20, which is turned laterally at its upper edge to provide a flange 21. The lower edge 30 of each plate 20 is turned laterally to provide a flange 22, the obliquity of the flange 22 being such that when it rests upon one of the inclined surfaces 19 of a horizontally disposed base member 12, the plate 20 is vertically disposed as shown in Fig. 2. The oblique flange 22, which constitutes the base 35 of each form center, is supplemented by a metal angle 23, the lower surface of which is disposed in the same plane with the lower surface of the oblique flange 22, so that the lower surfaces of angle 23 and the oblique flange 22 together constitute a form center base of substantial breadth. It is to be noted, however, that the breadth of the form 40 center base provided by angle 23 and oblique flange 22 is less than the breadth of the base member notches 18. The form center plates are stiffened at their lateral edges by steel angles 24, and may be provided with centrally disposed stiffening angles 25, if desired, the said angles 24 and 25 being riveted, welded or otherwise suitably secured to their associated plate 20, as shown in Fig. 1.

In utilizing the apparatus shown in Figs. 45 1 to 5 in the construction of a culvert or the

like, I make the usual excavation to the necessary depth, and then put in the usual concrete base or floor indicated at 26. After the concrete base or floor has set for some time, at least over night, I am ready to position 50 and assemble the form. The base members 12-12 are placed upon the concrete base 26, as shown in Figs. 1 and 2, the said base members 12 being disposed parallel to each other and being spaced a substantial distance 55 apart, the spacing of the base members 12 being determined by the size of form center employed. After the base members 12 have been placed in position, as shown in Fig. 1, the several form centers 13-13 are placed in 60 position. Each of the form centers is disposed upon one of the inclined base member surfaces 19 and are placed on corresponding sides of their adjacent base member notches 18. It will be noted that the oblique flange 65 22 of each form center is provided with two pairs of downwardly projecting fingers 27, which may be in the form of rivets tightly driven or welded in the positions shown. Each pair of fingers 27 is designed to engage 70 the vertical side of one of the base members 12, in order that the base members 12 may be held properly spaced apart.

While I have shown but one form center in Fig. 2, it will be understood that at least 75 two, and if desired a multiplicity, of these form centers will be employed, there being one form center disposed adjacent each one of the base member notches 18. The form center plates 20 and their lateral stiffening 80 angles 24 are cut away, as indicated at 28, to provide hooks 29, the purpose of these hooks being to retain the cover plates 14 and 15 in 85 position.

It will be noted that the flanges of the 90 cover plates 14 and 15 are suitably perforated to accommodate the hooks 29. I prefer to provide each flange of each cover plate with suitably spaced apertures, in order that the said cover plates may be used, either side 95 up or either end to.

After the form centers have been properly placed upon the base members 12, as hereinbefore described, the side cover plates 15 are placed in position. When the said side cover plates are positioned, as shown in Fig. 1, the form center hooks 29 pass freely through the apertures in the upper flanges of the side cover plates, and the lower flanges of the cover plates rest directly upon the base or floor 26. After the side cover plates 15 have been placed in position, the corner cover plates 14 are placed in position, the horizontal flange of each corner cover plate resting upon the upper flange of one of the side cover plates 15, and the vertical flange of each corner cover plate resting upon the form centers. The form center hooks 29, of course, pass freely 120 through the apertures of the horizontal 125 flanges of the corner cover plates 14. The 130

flanges of the corner cover plates, as is clearly illustrated in Figs. 1 and 4.

Attention is directed to the fact that the side cover plates 15 rest directly upon the 5 concrete base or floor 26, and derive none of their support from the form centers. Moreover, since the horizontal flanges of the corner cover plates rest upon the upper flanges of the side cover plates 15, the major 10 portion of the weight of the corner cover plates and the concrete placed thereon is supported by the base 20 through the cover plates 15. The various apertures through which the form center hooks pass are of 15 such size that lateral pressure upon the cover plates is taken up not by the hooks 29, but by the engagement of the form center edges with the cover plate flanges. The purpose of the hooks is to keep the form 20 centers stationary when the base members are driven out from under the form centers, as will presently be explained. The hooks are not intended to withstand lateral pressure upon the side cover plates.

25 After the form has been positioned and assembled as just described, the concrete which is to form the top and side walls of the culvert or other concrete structure under construction is poured over and around the 30 form center in the usual manner.

The lateral pressure of the concrete is taken up by the form centers, and not by the hooks 29, because of the heretofore mentioned loose fit between the hooks and the 35 cover plate apertures. Attention is also directed to the fact that the base member angles 17 effectually prevent the lateral pressure of the concrete from forcing the lower flanges of the side cover plates under 40 the base members.

45 After this concrete has been permitted to set a sufficient length of time, the base members 12 are struck with a maul or ax to drive them in the direction indicated by the feathered arrow of Fig. 2. Due to the fact that the form center hooks 29 engage in apertures in the cover plate flanges, as has been just described, the form centers remain stationary when the base 50 members are so moved. As soon as the notches of the base members are moved directly under the several form centers, the form centers drop out of engagement with the several cover plates and the entire form 55 collapses. The inclined surfaces 19 of the base members 12 coöoperating with the inclined bottom surfaces of the various form centers materially facilitate the collapsing of the form, because of the fact that when 60 the base members are struck, as just described, there is no tendency for the several parts to wedge. In fact, there is a decided tendency for the parts to loosen,—the direct opposite of a tendency to wedge.

65 At this point I will state that the means

carried by the form centers for spacing the base members 12 need not be in the form of the rivets 27 heretofore described. Any suitable and equivalent means may be provided for this purpose. For instance, in 70 Figs. 6 and 7 I have shown the fingers for engaging the upper edges of the base members as short metal angles 27^a, which are welded, riveted, or otherwise suitably secured to the under sides of the form center 75 flanges 22. The angles 27^a perform precisely the same function as do the rivets 27 hereinbefore described.

In Figs. 8 and 9 I have illustrated the adaptation of my invention to a form considerably higher and wider than the form shown in the preceding figures. The form of Figs. 8 and 9 differs essentially from that shown in the preceding figures only in the fact that more cover plates are required, 80 and in the fact that different form centers are employed. Each of the form centers of Figs. 8 and 9 is provided with a plurality of hooks 29, 29, at each of its lateral edges. These hooks coöperate with the apertures in 85 the side cover plates, for the purpose of steadyng these plates prior to the pouring of the concrete therearound, and to hold the form centers steady when the base members are driven independently of the form centers when the form is to be collapsed. It will be noted that all of the several side 90 cover plates 15 of Figs. 8 and 9 except the lowermost side cover plates rest directly upon the cover plate therebeneath, with the 95 result that the weight of all of the side cover plates is supported by the floor or base 26, none of the weight of these parts being carried by the form centers 13. It will be noted that since the form centers of Figs. 100 8 and 9 are considerably wider than the form centers of Figs. 1 to 5 inclusive, the horizontal sides of the corner cover plates 14 do not constitute a complete top for the form. For this reason I employ a plurality of top 105 channel members 15^a, which may be the same in all respects as the side cover plates 15. The flanges of the top cover plates 15^a need not necessarily be provided with apertures if they are intended always to be used 110 as top cover plates. However, by providing the flanges of the top cover plates 15^a with suitable apertures, these plates may be used 115 interchangeably with the side cover plates.

120 While I have shown but two sizes of form centers embodying my invention, it will be understood that my invention contemplates the provision of form centers of a great number of different sizes. I might state that I prefer to manufacture and sell an equipment 125 which is intended to be used in the construction of the form of my invention in a large number of sizes. Such an equipment comprises a pair of base members 12, which may be utilized in erecting a form of any 130

size, a pair of corner cover plates 14, which are also capable of being used in building a form of any size, as many of the channel members 15 and 15^a as may be required in connection with the form of largest size, and a plurality of sets of form centers 13, one set of these form centers being provided for every size form that the equipment is intended to provide.

10 In Fig. 11 I have illustrated a modified form center construction. In this construction the form center hooks shown at 29^a are formed separately from the form center plates, and are welded or riveted thereto.

15 The lateral edges of the form center and plates are notched adjacent to the bars 29^a, as indicated at 28^a, in order to accommodate the cover plate flanges, the notches being so conformed that lateral pressure of the concrete upon the side cover plates 15 may be taken up by the form centers and not by the hooks, as hereinbefore described.

While I have illustrated my invention in a number of characteristic embodiments, it 25 will be understood that I do not limit myself to these specific constructions, but desire to cover all similar and equivalent constructions coming within the terms and spirit of the appended claims.

30 What I claim as new and desire to secure by Letters Patent of the United States is:

1. A form of the class described comprising a pair of base members, each provided with a plurality of notches in its upper edge, 35 a plurality of form centers, said form centers adapted to rest upon said base members at points adjacent said notches, means carried by the form centers to space the base members from each other without preventing longitudinal movement of the base members independently of the form centers, hooks at the lateral edges of the form centers, side cover plates provided with flanges apertured to freely receive said hooks, the 40 weight of said side cover plates being carried by the floor or base whereon said base members rest, means carried by the base members for spacing the lower edges of the side cover plates from the base members, 45 said hooks having loose fits in their respective cover plate apertures, so that lateral pressure upon the side cover plates is transmitted directly to the form centers and not to said hooks, together with corner cover plates of substantially L-shaped cross section, the vertical sides of said corner cover plates being provided with flanges apertured to receive the form center hooks, said form centers adapted to drop so that the 50 aforesaid hooks become disengaged from the cover plates when the base members are driven to positions such that their notches lie directly beneath the form centers.

2. A form of the class described comprising a pair of base members each provided

with a plurality of notches in its upper edge, a plurality of form centers adapted to rest upon said base members at points adjacent said notches, means carried by said form centers to space said base members without 70 preventing longitudinal movement of the base members independently of the form centers, together with cover plates adapted to engage and space said form centers, said form centers arranged to drop out of engagement with said cover plates when said base members are driven to positions such that the base member notches lie beneath the form centers.

3. A form of the class described comprising a pair of base members each provided with a plurality of notches in its upper edge, a plurality of form centers adapted to rest directly upon said base members at points adjacent said notches, means carried by said 80 form centers to space said base members without preventing longitudinal movement of the base members independently of the form centers, together with cover plates adapted to engage and space said form centers, said form centers arranged to drop out of engagement with said cover plates when said base members are driven to positions such that the base member notches lie beneath the form centers.

4. In a form of the class described, the combination with a plurality of form centers, base members whereon said form centers rest, said base members when moved independently of the form centers adapted to 100 permit the form centers to drop to positions lower than the positions normally occupied thereby, hooks at the lateral edges of the form centers, and side cover plates provided with flanges apertured to receive said hooks, 105 said side cover plates arranged to hold the form centers stationary when the base members are moved as aforesaid, said hooks arranged to disengage the said cover plates when the form centers drop.

5. In a form of the class described, the combination with a plurality of form centers, base members whereon said form centers rest, said base members when moved independently of the form centers adapted to 115 permit the form centers to drop to positions lower than the positions normally occupied thereby, means carried by the form centers to space the base members from each other without preventing longitudinal movement 120 of the base members independently of the form centers, hooks at the lateral edges of the form centers, and side cover plates provided with flanges apertured to receive said hooks, said side cover plates arranged to 125 hold the form centers stationary when the base members are moved as aforesaid, said hooks arranged to disengage the said cover plates when the form centers drop.

6. In a form of the class described, the 130

- combination with a plurality of form centers, base members whereon said form centers rest, said base members when moved independently of the form centers adapted to 5 permit the form centers to drop to positions lower than the positions normally occupied thereby, hooks at the lateral edges of the form centers, and side cover plates provided with flanges apertured to receive said hooks, 10 said side cover plates arranged to hold the form centers stationary when the base members are moved as aforesaid, said hooks arranged to disengage the said cover plates when the form centers drop, said hooks arranged loosely to fit in their respective cover plate apertures so that lateral pressure upon the said cover plates is transmitted directly to the form centers through said flanges and not to said hooks. 15
- 20 7. In a form of the class described, the combination with a plurality of form centers, base members whereon said form centers rest, said base members when moved longitudinally independently of the form centers adapted to permit the form centers to drop to positions lower than the positions normally occupied thereby, cover plates disposed at the sides of said form centers, hooks at the lateral edges of said form centers, 25 said cover plates provided with apertured means engaged by said hooks, said hooks adapted to drop out of the apertures and thus disengage the cover plates when the form centers drop, as aforesaid.
- 30 8. In a form of the class described, the combination with a plurality of form centers, base members whereon said form centers rest, said base members when moved longitudinally independently of the form centers adapted to permit the form centers to drop to positions lower than the positions normally occupied thereby, means carried by the form centers to space the base members without preventing longitudinal movement of the base members independently of the form centers, cover plates disposed at the sides of said form centers, hooks at the lateral edges of said form centers, said cover plates provided with means engaged 35 by said hooks, said hooks adapted to disengage the cover plates when the form centers drop, as aforesaid.
- 40 9. In a form of the class described, the combination with a plurality of form centers, of base members whereon said form centers rest, said base members, when moved independently of the form centers, adapted to permit the form centers to drop to positions lower than the positions normally occupied thereby, hooks at the lateral edges of the form centers and side cover plates provided with flanges apertured to receive said hooks, said hooks having loose fits in their respective cover plate apertures so that lateral pressure upon the side cover plates is 45
- 50 transmitted directly to the form centers and not to said hooks.
10. In a form of the class described, the combination with a plurality of form centers, base members whereon said form centers rest, said base members when moved longitudinally independently of the form centers adapted to permit the form centers to drop to positions lower than the positions normally occupied thereby, means carried by 55 the form centers for spacing the base members from each other without preventing longitudinal movement of the base members independently of the form centers, side cover plates, and means for attaching the side cover plates to the form centers whereby the form centers are held stationary when the base members are moved longitudinally as aforesaid, said attaching means adapted to permit the form centers to drop independently of the side cover plates when the base members are moved to positions such that the form centers are permitted to drop, as aforesaid. 60
11. A form of the class described comprising a plurality of form centers, supporting means whereon the form centers are carried, said means adapted to be moved to permit the form centers to drop to positions lower than the positions normally occupied thereby, 65 side cover plates disposed at the sides of said form centers but having their weight carried by the surface on which said supporting means rests, flanges carried by said cover plates extending toward said form centers and engaging the same, and hooks carried by the form centers engaging in apertures in said flanges, said hooks adapted to disengage said flanges when the form centers drop, as aforesaid. 70
12. A form of the class described comprising a plurality of form centers provided at their lateral edges with upwardly projecting hooks, a plurality of cover plates provided with in-turned flanges adapted to bear against the form center edges, apertures in said flanges engaged by said hooks, and means for supporting said form centers, said means adapted to be operated to permit the form center hooks to drop out of said apertures, substantially as and for the purpose set forth. 75
13. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 80
14. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 85
15. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 90
16. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 95
17. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 100
18. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 105
19. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 110
20. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 115
21. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 120
22. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 125
23. A form of the class described comprising a plurality of form centers provided at their lateral edges with upwardly projecting hooks, a plurality of cover plates provided with in-turned flanges adapted to bear against the form center edges, apertures in said flanges engaged by said hooks, said hooks fitting loosely in said apertures, and means for supporting said form centers, said means adapted to be operated to permit the form center hooks to drop out of said apertures, substantially as and for the purpose set forth. 130

14. In a form of the class described, a pair of base members provided with a plurality of notches and inclined upper surfaces adjacent said notches, a plurality of form centers adapted to rest on said base members at said inclined surfaces, means carried by the form centers to space the base members without preventing longitudinal movement of the base members independently of the form centers, together with side cover plates adapted to engage said form centers to hold the latter stationary when the base members are moved relatively to the form centers.

15. A form of the class described, comprising a plurality of form centers, parallel base members whereon the form centers are carried, said base members adapted to be moved to permit the form centers to drop to positions lower than the positions normally occupied thereby, side cover plates

disposed at the sides of said form centers but having their weight carried by the surface on which said base members rest, said side cover plates and form centers having inter-engaging members which are adapted to disengage when the form centers drop as aforesaid and means carried by the base members and projecting laterally therefrom to engage the lowermost side cover plates near the lower edges thereof to prevent the lowermost side cover plates from being forced by lateral pressure out of alinement with the cover plates thereabove.

In witness whereof, I hereunto subscribe my name this 6th day of April, 1920.

HARRY E. BILGER.
